PISTON GROOVE CLEANER AND RING COMPRESSOR

Filed April 22, 1929

Inventor,
Martin L. Decker
By Roy E. Hamilton
Attorney.

UNITED STATES PATENT OFFICE

MARTIN L. DECKER, OF KANSAS CITY, MISSOURI

PISTON GROOVE CLEANER AND RING COMPRESSOR

Application filed April 22, 1929. Serial No. 357,110.

This invention relates to tools operating in conjunction with the piston and cylinder of internal combustion motors, and has for its object the novel means for removing the 5 carbon from the piston ring grooves and also to serve as a ring compressor to facilitate the assembling of the piston and piston rings in the cylinder.

A further object of the present invention 10 is the provision of a tool having a substantially circular resilient body portion and two outwardly extending arms, one of which is provided with a plurality of bits which are adapted to be adjusted into and out of the 15 confines of said circular body portion.

Another object of this invention is to produce a simple, inexpensive and handy tool that is adjustable to pistons of different sizes and one that will effect results without the 20 expenditure of unnecessary time.

With the foregoing and other objects in view, reference will now be made to the accompanying drawings in which the preferred form of the invention is shown.

25 Figure 1 is a perspective view of a tool embodying this invention;

Fig. 2 is a plan view of a piston, partly broken away, with the tool positioned thereon and with the bit engaging the piston ring 30 groove. Said tool is partly in section;

Fig. 3 is a side elevation of Fig. 2 with parts broken away;

Fig. 4 is a plan view of the piston partly broken away and with the tool in position, 35 with the bits retracted, compressing a piston ring into the piston groove.

Like reference characters designate similar parts throughout the several views and the numeral 10 denotes a piston of the conventional type having piston ring grooves 11. The piston ring 12 is of the ordinary split type, which should be fitted into a groove that is free from carbon or any other foreign substance.

45 The tool embodying the invention comprises a substantially circular body portion 14 having spaced apart arms 15 and 16 constituting a handle by means of which the tool is operated. The tool is preferably made of 50 resilient ribbon stock with the circular body

portion made of sufficient internal diameter to span a piston and adapted to be reduced by drawing the arms toward each other, to substantially fit the piston. With this construction the body portion may be adjusted 55 to fit pistons of different sizes within certain limits. Furthermore, the body portion is entirely free from holes or notches and therefore will flex uniformly throughout its entire length, thereby maintaining a substantially circular form at all compressed positions.

Bits 17 and 18 are mounted on the inner surface of 15 for rotatable and longitudinal slidable movement by means of bolt 19 passing through longitudinally disposed slots 20 and 21 formed in 17 and 18 respectively, then through hole 22 formed in arm 15. Bolt 19 is threaded and provided with a thumb nut 23 by means of which the bits may be securely clamped in a fixed position.

Bit 17 is shown with a cutting blade 24 at each end thereof, while bit 18 has a cutting blade 25 at one end only. Each cutting blade may be made of a different width, as shown, 70 to fit ring grooves of different sizes.

Referring to Fig. 2, it will be noted that the bit 17 is positioned on the arm 15 so that the blade 24 projects into the inscribed circle of the body member and contacts all 80 sides of the groove 11 so that, as the tool is rotated about the piston, all foreign substances will be removed from the walls of the groove. Should it be desired to clean a narrower groove, thumb nut 23 is loosened and the desired cutter positioned so as to engage the groove and the thumb nut again tightened.

In Fig. 4 the bits are shown positioned outside the confines of body member 14 so that 90 the tool may be used to compress the piston ring 12 as the piston is being inserted into the cylinder. This operation is accomplished by gripping the ring with the body portion of the tool, with a portion of the ring extending below said body portion. When the ring is compressed the portion of the ring extending below the tool is inserted in the cylinder, then the tool may be removed and the entire ring 95 pressed into the cylinder.

It is important to note that the width of the bits are no wider than the arms so that they do not protrude therebeyond to prevent the lower plane of the tool being moved down into the plane of the upper end of the cylinder. In other words all parts of the tool lie wholly within parallel planes determined by the opposite edges respectively of the body member. With this form of tool either side thereof may be used next to the cylinder when compressing the rings.

The bits are so positioned on the arm 15 that they also prevent undue flexing thereof when the arms are forced together against the action of spring tension of the body portion. Without this reinforcement, arm 15 would tend to flex more adjacent the hole 22. Any desired number of bits may be provided, also bits may be placed on either or both arms.

I do not wish to limit this invention to the structure shown and described since many modifications may be made without departing from the spirit of the appended claims.

What I claim is:

1. A tool of the character described comprising a resilient, curved body member of substantially circular form, spaced apart arms extending outwardly from opposite extremities respectively of said body member, a bit carried by one of said arms and means attaching said bit to the arm permitting rotatable and longitudinal adjustment of said bit.
2. A tool of the character described comprising a resilient, curved body member of substantially circular form, spaced apart arms extending outwardly from opposite extremities respectively of said body member, and a bit carried by one of said arms having a longitudinal slot therein, a bolt carried by the arm passing thru said slot and means associated with the bolt to tighten the same.
3. A tool of the character described comprising a resilient, curved body member of substantially circular form, spaced apart arms extending outwardly from opposite extremities respectively of said body member, and a radially adjustable bit carried by one of said arms, said bit lying in a plane parallel with the arm and slidably secured thereto for longitudinal movement.
4. A tool of the character described comprising a resilient, curved body member of substantially circular form, spaced apart arms extending outwardly from opposite extremities respectively of said body member, and a bit having a blade at each of its opposite ends, rotatably mounted intermediate its ends whereby either of the blades may be presented to the work.

In testimony whereof, I hereunto affix my signature.

MARTIN L. DECKER.
